WORK CENTERING AND HOLDING MACHINE

Frank Morgan, Healdton, Okla.

Original application July 28, 1937, Serial No. 156,247. Divided and this application July 18, 1938, Serial No. 219,901

10 Claims. (Cl. 51—241)

Rotatable drill pipe is made up of sections usually from 40 to 44 feet in length, eight inches or so in diameter, and of great weight, one end of each pipe section having a flared box, into which the pin of an adjoining pipe section is adapted to be threaded, the pipe sections being provided with transverse shoulders (varying in width as desired), the threads of the pin and of the box coming to a jam at the time the shoulders arrive at engagement. In operation, the drill pipe (composed of many sections) is rotated, usually at moderately high speed, liquid being pumped in at the top of the drill pipe and the liquid escaping at the bottom, through outlets 15 in the drill proper, the liquid rising between the drill pipe and the wall of the well.

When the drill becomes dull, or ceases to cut, for that reason or some other, the drill pipe is withdrawn and unjointed, a new bit is put on, 20 the drill pipe is returned to the well-hole, and drilling is resumed. The repeated unjoining and rejoining of the sections of the drill pipe, in addition to vibration which takes place in the well, wears the joints. Owing to the diameter at 25 the joints, the joints are subjected to heavy wear, and the joint-forming elements become grooved, flattened or greatly worn. Hardening often takes place along the entire face of the joint-shoulder or along a part only of the shoulder, or sometimes in spots, the degree of hardness being such that no lathe-cutter can work upon them, unless they are annealed.

A constant wearing of the threads of the pin and of the box takes place, and since there may 35 be little or no wear on the shoulders, the threads fail to make a perfect fit and all the strain is thrown on the shoulders, with a strong tendency to draw the threads.

Experience has taught that by dressing back 40 the shoulders and by using a master jig or gauge to position the work properly for dressing, the life of the drill joint is practically doubled. The shoulders must be in planes exactly at right angles to the axis of the pipe section. Owing to 45 conditions arising out of wear, and to the warped or crooked condition of the pipe section, chucking in a lathe is not practical, and is almost an impossibility.

In view of the foregoing, two problems are 50 presented; the shoulders must be dressed properly; and the work must be positioned and held properly and conveniently whilst the dressing operation is being carried out. My copending application Serial No. 156,247, filed July 28, 1937, 55 shows means for accomplishing both of the ends

last-above referred to; but inasmuch as it has been ruled that the work-dressing and work-holding instrumentalities which I have invented are divisibly-distinct inventions, I am hereby dividing my aforesaid application, the present disclosure being confined to the work-holding and work-positioning mechanism. 5

Recalling that the pipe sections are from 40 to 44 feet long, eight inches or thereabout in diameter, and of great weight, that there are 10 many of them, that they cannot be centered properly on a lathe, and that there are no means for centering and positioning them at the well or place of use, it has been necessary to haul them a long distance heretofore, with corresponding expense, and with the high probability that, when the shop is reached, no adequate work-positioning device will be available. It is desirable, therefore, to be able to position and hold the work on the job, and not only to 15 position and hold the work on the job but, as well, to position and hold it properly there. Those results are accomplished by the device forming the subject-matter of this application.

It is within the province of the disclosure to 20 improve generally, and to enhance the utility of, devices of the type to which the present invention appertains.

With the above and other objects in view, which will appear as the description proceeds, 30 the invention resides in the combination and arrangement of parts and in the details of construction hereinafter described and claimed, it being understood that changes in the precise embodiment of the invention herein disclosed, 35 may be made within the scope of what is claimed, without departing from the spirit of the invention.

In the drawings:

Fig. 1 shows in front elevation, a tool constructed in accordance with the invention; 40

Fig. 2 is a horizontal section on the line 2—2 of Fig. 1, parts being shown in elevation;

Fig. 3 is a transverse section on the line 3—3 of Fig. 1, the view showing the pin end of the 45 pipe in place;

Fig. 4 is a transverse section similar to Fig. 3 but showing the box end of the pipe in place;

Fig. 5 is a front elevation of the chuck-supporting body;

Fig. 6 is a sectional view showing a modified means for holding the jig on the rotatable member;

Fig. 7 is a sectional view illustrating the means whereby the slide is mounted;

55

Fig. 8 is a sectional view showing the mounting of the chuck carrier on the chuck-supporting body;

Fig. 9 is a side elevation of the chuck carrier 5 and the chuck;

Fig. 10 is an elevation wherein the chuck carrier is viewed edgewise.

The device forming the subject-matter of this application comprises an annular (Fig. 5) chuck-supporting body 1, provided with any desired number of radial guides 2 (Figs. 2 and 8), wherein chuck carriers 3 are mounted for right-line reciprocation. Toothing chucks 4 (Figs. 2 and 9) are pivotally mounted at 5 on the inner ends of 15 the chuck carriers 3 and because of their pivotal mounting, the chucks will grip a pipe section 81 of Fig. 2) properly, regardless of irregularities in the pipe.

Feed screws 6 (Figs. 2 and 8) are mounted 20 rotatably, but held against endwise movement, in seats 7 formed in the body 1. The feed screws 6 engage in threaded trough-shaped recesses 8 formed in the chuck carriers 3, and by rotating the feed screws, the chuck carriers 3 and the 25 chucks 4 may be adjusted in and out, radially of the body 1, until the pipe section 81 is gripped.

The chuck-supporting body 1 is received partially within an annular carrier 9 (Fig. 2) having a projecting rim 10 which is extended about 30 the body. An annular centering guide 11 (Figs. 5 and 2), made of special bearing metal, is secured to the body 1 and is received in an annular groove 14 formed in the carrier 9. That side of the carrier 9 which is opposite to the groove 35 14 is provided with an annular rib 15, the function of which will be made manifest hereinafter. The rib 15 shows best in Figs. 1, 3 and 4.

A sprocket wheel 16 (Figs. 1 and 2), made in two pieces, is attached to the edge of the rib 40 10 of the rotatable carrier 9 and extends into an annular groove 18 formed in the periphery of the body 1, the construction being such that, by means of the sprocket wheel, the carrier 9 is connected to the body 1 for rotation with respect 45 thereto.

The sprocket wheel 16 is engaged by a sprocket chain 22, cooperating with a small driving sprocket wheel 23 (Fig. 1) secured to a shaft 24 mounted to rotate in an offset bracket 25 (Figs. 1 and 5) 50 attached to the edge of the body 1. The shaft 24 may be power-rotated, by any suitable means, not shown in the drawings but accessible at the place of use.

An under-cut guide plate 45 (Figs. 1, 2 and 7) 55 is secured to the rotatable carrier 9, and on the guide plate, a slide 46 is mounted for right-line adjustment, radially of the carrier 9. A post 48 extends through the guide plate 45 (Fig. 2), and is secured at 49 to the rotatable carrier 9. The post 48 extends outward into an elongated recess 31 in the slide 46. A feed screw 47 is located in the recess 31, the inner end of the feed screw being threaded into the post 48 on the rotatable carrier 9, the feed screw being journaled in the 65 outer end wall of the slide 46, and being held against longitudinal movement by collars 50 attached to the feed screw. It may be observed that, in my aforesaid application Serial No. 156,247, the slide 46 functions as a tool carriage, 70 that function, however, being something with which the present application has nothing to do, the slide 46, withal, having a function (to be brought out hereinafter) in the work-mounting and work-positioning machine constituting the 75 raison d'etre of the case at bar.

The numeral 72 in Figure 4 marks a setting jig, provided with arms 73 having seats 74 adapted to receive the rib 15 on the rotatable carrier 9, the jig being centered thereby with respect to the carrier. The setting jig 72 is provided with 5 a tapered hub 75, which has an external thread 76. In Figs. 3, 2 and 1 there is shown a setting jig 77 having arms 78 provided with seats 79 adapted to receive the rib 15 on the rotatable carrier 9. The jig 77 has a central tapered bore, 10 provided with an internal thread 80. The jigs 72 and 77 have, each, a collar 200, provided with oppositely-disposed holes 201.

The numeral 81 marks a pipe supplied at one end with a tapered pin 82 (Figs. 3 and 1), having 15 an external thread 83. At its opposite end (Fig. 4), the pipe 81 has what is commonly known in the art as a tapered box 84, supplied with an internal thread 85, the thread 85 on the box 84 of one pipe section being adapted to cooperate 20 with the thread 83 on the pin 82 of the next adjoining pipe section, a shoulder 87 around the pin 82 being adapted to abut against a shoulder 89 at the end of the box 84, simultaneously with the grip of the pin thread 83 with the box thread 85. The shoulders 87 and 89 have to be dressed if they are to cooperate properly, and this invention supplies means for so positioning and holding either end of the pipe 81 that the aforesaid dressing 25 may be accomplished properly.

Assuming that the shoulder 87 of the pipe 81 is to be worked upon, as in Figs. 3 and 2, the pipe is laid down horizontally on horses (not shown). The body or jig support 1 and the jig-carrier 9 are slipped over the pipe. The pin 82 of the pipe 35 is threaded into the jig 77. The arms 78 of the jig 77 are connected to the carrier 9 by removable attaching elements 86, the rib 15 of the carrier 9 being received in the seats 79 in the arms 78 of the jig 77, the securing elements, independently 40 of the rib 15 and the seats 79, constituting means for centering the jig 77 with respect to the jig support 1 and the jig carrier 9. Thus the rotatable member 9 and the body 1 are centered with respect to the pipe 81. By means of the feed 45 screws 6 of Fig. 2, the chuck carriers 6 and the chucks 4 are advanced until the chucks grip the pipe 81. Thus the body 1 is coupled to the pipe 81 and the jig 77 can be taken off, by removing the attaching elements 86 and rotating the jig 50 77. The member 9 rotates along with the jig 77 during this operation because of the interengaging parts 46 on the jig carrier 9 and 78 on the jig. The rotation of the jig 77 can be accomplished in two ways. A bar (not shown) may be 55 inserted through the holes 201 on the collar 200 of the jig 77, the turning of the jig then being done by hand. Owing to the size and weight of the parts, and to other conditions, a hand-turning of the jig 77 is not always the best mode of 60 procedure, and the machine affords another means to the desired end.

Recalling that the screws 86 of Figs. 3 and 1 have been taken out, the jig 77 is capable of moving in the direction of the arrow A in Fig. 3, and likewise is free to rotate with the carrier 9, rotation being imparted to the jig 77, from the carrier, by a cooperation of parts to be explained hereinafter. The carrier 9 can rotate on the 70 body 1, the body being held to the pipe 81 by the chucks 4. The operator moves the slide 46 (Fig. 1) in or out on the carrier 9, by means of the screw 47 (Fig. 2), until the inner portion of the slide is in a position to engage one of the 75

arms 78 of the jig 77 when the carrier 9 is rotated.

The carrier 9 can be power-rotated by means of the shaft 24 of Fig. 1, the sprocket wheel 23, 5 the chain 22, and the sprocket wheel 16 of Figs. 1 and 2. When the carrier 9 is rotated, the slide 46 of Fig. 1 moves in an orbit, the inner portion 10 of the slide engages one of the arms 78 of the jig 77, the jig is rotated, and the jig is threaded off the pin 82 of the pipe 81, by power, and responsive to a degree of force that an operator cannot exert.

When the box end 84 of the pipe 81 is to be operated upon, the jig 72 of Fig. 4 may be employed, it being unnecessary to trace out the mounting of the jig 72, in view of what has been stated hereinbefore with respect to the jig 71.

It is not insisted that the attaching elements 86 of Figs. 3 and 4 be used to secure the jigs 72 20 and 71 to the rotatable member 9. For example, a clamp frame 88 and a screw 92 may be employed, as shown in Fig. 6. In Fig. 6, parts hereinbefore described have been designated by numerals already used, with the suffix "a".

25 What is claimed is:

1. In a pipe-centering device, an annular jig support, pipe-gripping chucks mounted for right-line movement on the jig support, toward and away from the axis of the jig support, means 30 under the control of an operator for imparting the aforesaid movement to the chucks, an annular rotatable carrier including a rim within which the jig support is received, a first sprocket wheel secured to the rim and cooperating with the jig 35 support to hold the carrier on the jig support for rotation, a power-driven shaft journaled in the jig support, a second sprocket wheel on the shaft, a sprocket chain engaged with the sprocket wheels, a jig having arms, the jig and the carrier 40 having detachably interengaged parts which center a pipe with respect to the chucks, the jig having a threaded portion for engagement with the thread of a pipe, means for securing the arms of the jig detachably to the carrier, a slide 45 mounted to reciprocate on the carrier, and means under the control of an operator for adjusting the slide to a position in which it will engage one of the arms of the jig, when the carrier is rotated.

2. In a pipe-centering device, an annular jig 50 support, a pipe-gripping means under the control of an operator and mounted for movement on the jig support, toward and away from the axis of the jig support, an annular rotatable carrier including a rim within which the jig support is received, a first sprocket wheel secured to the rim and cooperating with the carrier 55 on the jig support for rotation, a power-driven shaft journaled in the jig support, a second sprocket wheel on the shaft, a sprocket chain engaged with the sprocket wheels, a jig having arms, the jig having a threaded portion for engagement with the thread of a pipe, means for securing the arms of the jig detachably to the carrier, and movable means on 60 the carrier and under the control of an operator for engaging one of the arms of the jig, when the carrier is rotated, to unthread the jig from a pipe.

3. In a pipe-centering device, an annular jig 65 support, pipe-gripping chucks mounted for right-line movement on the jig support, toward and away from the axis of the jig support, means under the control of an operator for imparting the aforesaid movement to the chucks, an annular rotatable carrier including a rim within which the jig support is received, a first sprocket wheel 70 secured to the rim and cooperating with the jig support to hold the carrier on the jig support for rotation, power-driven means for rotating the carrier, a jig having arms, the jig and the carrier 75

the jig support, an annular rotatable carrier mounted on the jig support for rotation, a power-driven shaft journaled in the jig support, means for rotating the carrier from the shaft, a jig having arms, the jig having a threaded portion for engagement with the thread of a pipe, means for securing the arms of the jig detachably to the carrier, a slide mounted to reciprocate on the carrier, and means under the control of an operator for adjusting the slide to a position in which it will engage one of the arms of the jig, when the carrier is rotated, and unthread the jig from a pipe.

4. In a pipe-centering device, an annular jig support, pipe-gripping means under the control of an operator and mounted for movement on the jig support, toward and away from the axis of the jig support, an annular rotatable carrier mounted on the jig support for rotation, power-driven means for rotating the carrier, a jig having arms, the jig having a threaded portion for engagement with the thread of a pipe, means for securing the arms of the jig detachably to the carrier, a slide mounted to reciprocate on the carrier, and means under the control of an operator for adjusting the slide to a position in which it will engage one of the arms of the jig, when the carrier is rotated, and unthread the jig from a pipe.

5. In a pipe-centering device, an annular jig support, pipe-gripping means under the control of an operator and mounted for movement on the jig support, toward and away from the axis of the jig support, an annular rotatable carrier mounted on the body for rotation, power-driven means for rotating the carrier, a jig having arms, the jig having a threaded portion for engagement with the thread of a pipe, means for securing the arms of the jig detachably to the carrier, and movable means on the carrier and under the control of an operator for engaging one of the arms of the jig, when the carrier is rotated, to unthread the jig from a pipe.

6. In a pipe-centering device, an annular jig support, pipe-gripping chucks mounted for right-line movement on the jig support, toward and away from the axis of the jig support, means under the control of an operator for imparting the aforesaid movement to the chucks, an annular rotatable carrier including a rim within which the jig support is received, a first sprocket wheel secured to the rim and cooperating with the jig support to hold the carrier on the jig support for rotation, a power-driven shaft journaled in the jig support, a second sprocket wheel on the shaft, a sprocket chain engaged with the sprocket wheels, a jig having arms, the jig having a threaded portion for engagement with the thread of a pipe, means for securing the arms of the jig detachably to the carrier, and movable means on the carrier and under the control of an operator for engaging one of the arms of the jig, when the carrier is rotated, to unthread the jig from a pipe.

7. In a pipe-centering device, an annular jig support, pipe-gripping chucks mounted for right-line movement on the jig support, toward and away from the axis of the jig support, means under the control of an operator for imparting the aforesaid movement to the chucks, an annular rotatable carrier including a rim within which the jig support is received, a first sprocket wheel secured to the rim and cooperating with the jig support to hold the carrier on the jig support for rotation, power-driven means for rotating the carrier, a jig having arms, the jig and the carrier

- having detachably interengaged parts which center the jig with respect to the chucks, the jig having a threaded portion for engagement with the thread of a pipe, means for securing the arms 5 of the jig detachably to the carrier, a slide mounted to reciprocate on the carrier, and movable means on the carrier and under the control of an operator for engaging one of the arms of the jig, when the carrier is rotated, to unthread the jig 10 from a pipe.
8. In a pipe-centering device, an annular jig support, pipe-gripping means under the control of an operator and mounted for movement on the jig support, toward and away from the axis of 15 the jig support, a rotatable jig carrier mounted to turn on the jig support, a jig having means for receiving a turning device, whereby the jig may be rotated, the jig having a threaded portion for engagement with the thread of a pipe, and means 20 for securing the jig detachably to the carrier.

9. In a pipe centering device, a jig support, a jig carrier journaled on the support for rotation about the axis of the support, a jig, removable means for securing the jig to the carrier, and for centering the jig with respect to the jig support and the carrier, movable means on the support for centering a pipe with respect to the jig, the jig carrier and the jig, to enable the pipe to be threaded on the jig, interengaging parts on the jig and on the carrier, coacting to rotate the 10 jig and unthread it from a pipe when the carrier is rotated and after said removable means has been detached, said coacting part on the carrier being movable into and out of the path of the corresponding coacting part of the jig, and 15 mechanism for rotating the carrier.

10. In a pipe centering device, the structure defined in claim 9, in combination with means for mounting said mechanism on the support.

FRANK MORGAN. 20
